UNITED STATES PATENT OFFICE.

LEO J. WAHL, OF STERLING, ILLINOIS.

ELECTROMAGNET CONSTRUCTION.

Application filed September 25, 1925. Serial No. 58,592.

My invention relates to electro-magnets and more particularly to the core construction of an electro-magnet particularly adapted for use in a restricted space.

It is a purpose of my invention to provide an electro-magnet that is of minimum length for the amount of power obtainable therefrom and to provide a construction therefor that is of maximum efficiency. The 10 electro-magnet embodied in my invention is particularly adapted for use in such devices as electro-magnetically operated clippers in which the coil of the electro-magnet extends transversely of the casing of the 15 device. In such a device, it is particularly important that the same is so constructed that it will have a minimum width at the portion thereof where it is gripped by the hand of the operator. It is accordingly 20 very important to make the coil and core of the electro-magnet as short as is possible to still obtain the desired amount of power therefrom.

It is particularly a purpose of my invention to provide a core for an electro-magnet of this character that is so constructed as to provide a better path for the magnetic flux than has previously been the case.

It is particularly important in a device of this character to reduce the width of the core portions that lie between the end of the coil and the casing. In order to do this, the thickness thereof is increased to thus obtain substantially the same cross sectional area for the portion of the core lying between the casing and the end of the coil as would be the case if the same were made of a greater width at said portion. This has been previously accomplished by inserting laminations in the core that do not extend through the coil, but which extend transversely thereof between the casing and the end of the coil. Preferably, these laminations have end portions that are wider than the transversely extending portions thereof so that screws or other securing devices can be passed through the same for holding the same in position in the casing. The laminations that extend through the center of the coil are provided with similar transversely extending portions having similar ends. In the arrangement with the inserted laminations or added laminations, however, there are numerous air gaps in the path of the flux due to the fact that the flow is partially, in the transversely extending portion of the

core, from certain laminations that continue into the center of the coil to the laminations that do not extend into said center.

It is a purpose of my invention to increase 60 the efficiency of the electro-magnet further by eliminating said air gaps. This is accomplished by making the transversely extending portions of the core or the portions lying between the casing and the end of the coil of laminations, all of which continue into the center of the coil. In order to at the same time obtain the desired narrowness and thickness of this portion of the core, I bend the laminations in the portion of the core 70 extending transversely of the coil at an angle, preferably a right angle, to the portions thereof extending through the center of the coil in the form shown herein to obtain the desired amount of iron in the core 75 at this point.

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person 85 skilled in this art and as would fall within the scope of the claims.

In the drawings:

Fig. 1 is a view partly in vertical section and partly in elevation of an electro-magnetic clipper embodying my invention; 90

Fig. 2 is a plan view thereof showing the major portion of the cover broken away and taken substantially on the line 2—2 of Fig. 1;

Fig. 3 is a section taken on the line 3—3 95 of Fig. 1; and

Fig. 4 is a perspective view of one of the laminations.

Referring in detail to the drawings, my invention is shown as being applied to a clipper having a casing comprising the main body portion 10 and the cover 11, the cover being held in place on the main body portion by any suitable fastening means such as those indicated by the numeral 12 in Fig. 2. The main body portion 10 of the casing is provided with a pair of upwardly extending lugs or bosses 13 for supporting the electro-magnet comprising the coil 14 on said casing. 100 105

The coil 14 is wound on a core comprising a central main core portion 15 lying within and extending through the coil 14, a portion 110

16 extending transversely of the coil and portions 17 that lie on opposite sides of the coil 14 and extend substantially parallel to the central core portion 15. The transversely extending portion 16, it will be noted, is quite narrow as compared to the ends 17 and lies between the side wall 18 of the casing and the end of the coil 15 adjacent thereto, the other side wall being indicated by the 10 numeral 19 in Fig. 2. The end portions 17 are made wider in order to provide sufficient material for extending the fastening means 20 through the same. While the portions 16 are made narrow in order to reduce the 15 width of the casing between the walls 18 and 19 as much as possible and yet get as long a coil between said walls as is possible without increasing the distance between said walls, the portion 16 is furthermore thickened in order to provide a greater amount 20 of material in the portions of the core extending transversely of the coil than would be possible if the same were made any thicker than the central portion 15 thereof. 25 In order to obtain the desired shape to the core with the thickened transversely extending portion and yet have the magnetic flux travel through the iron throughout the length of the core without passing across 30 any air gaps, the laminations are made as shown more clearly in Figs. 3 and 4.

Referring to Fig. 4, it will be seen that each lamination comprises a central core forming portion 21 and ears 22 lying in substantially the same plane as the central core forming portion 21 to provide the ends 17 for the core. A transversely extending portion 23 connects the ends or ears 22 of each lamination with the central portion 21. Said 40 transversely extending portion is bent or flanged as indicated at 24 to provide a portion extending at an angle to the ends 22 and the central portion 21 lying preferably in a plane substantially at right angles to the 45 plane of the portions 21 and 22. Preferably, the blanks are made substantially alike and are bent over or flanged after being assembled, the blanks being held in proper relation by any suitable means so as not to shift 50 relative to each other. This causes the flanges 23 to have a stepped formation, such as clearly shown in Fig. 3, because of the thickness of the outer laminations which cause the bend in each successive inner lamination to be at a point nearer the edge 55 thereof. While it is not particularly necessary to have the stepped formation, this simplifies the method of making the core due to the fact that the blanks are all alike before 60 assembling.

Said electro-magnet is provided with the usual end members 25 for the coil 14, the flanges 24 being ordinarily clinched against one of said end members, as shown in Fig. 3. Cooperating with the electro-magnet is a

vibratory armature 26 carrying a movable clipper blade 27 which cooperates with a stationary blade 28 in a well known manner. The armature 26 is offset inwardly at 29 and 30 so as to have the said portions 29 and 30 thereof lie near the ends 17 of the core, thus having an offset to accommodate the coil and core of the electro-magnet. Said vibratory member is preferably clamped in position by suitable clamping means 31 and is vibrated by alternating current passing through the electro-magnet in a well known manner.

Having thus described my invention, what I desire to claim and secure by United States Letters Patent is:

1. In a device of the character described, a casing, an electro-magnet having a coil lying transversely of said casing and a core in said coil having a portion lying between the end of said coil and said casing, said core comprising laminations having portions extending at an angle to the axis of said coil lying between said casing and said coil.

2. In a device of the character described, a casing, an electro-magnet having a coil lying transversely of said casing and a core in said coil having a portion lying between the end of said coil and said casing, said core being laminated, and the portion thereof lying between the end of said coil and said casing projecting transversely of said coil beyond the portion thereof in said coil, all the laminations of said core externally of said coil extending into said coil.

3. In a device of the character described, a casing, an electro-magnet having a coil lying transversely of said casing and a core in said coil having a portion lying between the end of said coil and said casing, said core comprising laminations having portions extending substantially parallel to the axis of said coil and portions extending substantially perpendicularly to said axis lying between said casing and said coil.

4. In an electro-magnet, a core comprising laminations having flanges thereon extending transversely of said core, said flanges having projections at the ends thereof extending parallel to and in the planes of said laminations.

5. In a device of the character described, a casing, an electro-magnet having a coil lying transversely of said casing and a core in said coil, said core comprising laminations having flat portions within said coil extending substantially parallel to the axis thereof and portions lying between said casing and said coil extending to the periphery of said coil, said casing and core having cooperating means thereon holding said coil in position transversely of and in spaced relation to said casing.

6. In a device of the character described, a casing, a pair of spaced supports therein, an electro-magnet having a coil between said

supports and a core in said coil, said core having oppositely directed portions extending outwardly beyond the periphery of said coil at one end thereof and secured to said supports.

7. In a device of the character described, a casing, a pair of spaced supports therein, an electro-magnet having a coil between said supports and a core in said coil, said core comprising laminations having portions inside said coil extending substantially parallel to the axis thereof, portions outside said coil secured to said supports and intermediate portions extending transversely of said coil at one end thereof connecting said inside and outside portions, said intermediate portions being bent substantially right angles to the plane of said inside portions.

10 15

a casing, a pair of spaced supports therein, an electro-magnet having a coil between said supports and a core in said coil, said core 20 comprising laminations having portions inside said coil extending substantially parallel to the axis thereof, portions outside said coil secured to said supports and intermediate portions extending transversely of said coil 25 at one end thereof connecting said inside and outside portions, said intermediate portions being bent substantially right angles to the plane of said inside portions.

In witness whereof, I hereunto subscribe 30 my name this 15th day of September, A. D. 1925.

LEO J. WAHL.

8. In a device of the character described,
